GARDEN HOSE SUPPORT

John W. Wiegand, 4004 Stinson Blvd., Minneapolis, Minn.

Filed July 15, 1960, Ser. No. 61,375

Term of patent 14 years

(Cl. D91—1)

I claim:

The ornamental design for a garden hose support, as shown.
